(57) **CLAIM**

The ornamental design for a table, as shown and described.

DESCRIPTION

FIG. 1 is a perspective view of a table; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is another perspective view thereof; and, FIG. 9 is further another perspective view showing the table stacked with another table in a folded mode. The claimed design is indicated by the relatively dark portions in the drawings, while the relatively light portions enclosed by broken lines are environmental and form no part of the claimed design. Shading is used to illustrate the curvature of the part and not color. The broken lines in FIG. 9 depict environmental subject matter and form no part of the claimed design.
